APPARATUS FOR STERILIZING AND SUBSEQUENTLY COOLING FOOD IN CLOSED CONTAINERS

Kaare Omsted, Oslo, Norway

Application January 9, 1933, Serial No. 650,844
In Norway May 19, 1932

4 Claims. (Cl. 126—272)

This invention relates to an apparatus for sterilizing and subsequently cooling food in closed containers, such as, for instance, containers of tin, glass or earthenware etc., the process being carried out in a retort, in a liquid under pressure, the pressure in the retort being kept constant or approximately so during the sterilizing step or stage as well as during the cooling stage. By regulation of this pressure in such a way that it is equal to or greater than the internal pressure in the containers due to the expansion of the goods and the air in the containers as well as to development of steam in the same during the heating process, any danger of a bulging of bottom and lid of the containers or of other damage to or bursting of the same owing to the internal pressure is avoided. The pressure in the retort therefore should be maintained until the container with its contents has been cooled down substantially.

According to the invention the retort during the sterilizing stage as well as the cooling stage is kept completely filled with liquid under pressure, during the sterilizing stage of the steam is supplied at a higher pressure than the working pressure of the retort, this admission of steam being regulated in accordance with the temperature in the retort; during the cooling process cooling water at a pressure equal to or higher than the working pressure is introduced into the retort.

For compensating for possible drop in pressure during operation a container is provided communicating with the retort, in which container a quantity of liquid is accumulated under a hydraulic pressure or air pressure, equal to the working pressure of the retort. In the event of a drop in pressure in the retort part of the liquid in the said container then immediately will flow over into the retort and substantially restore the pressure in the same.

The said container may be of the closed type, into which liquid from the retort flows when the retort is being put under pressure, whereby the air in the container is compressed and consequently immediately will force some liquid back into the retort if the pressure in the same for some reason or other should fall. The container may be a dome located directly on the retort or it may communicate with the retort through a suitable conduit, in which latter case a water seal preferably is provided in the conduit in order to prevent steam from the retort from entering the container.

Instead of utilizing air pressure in the container, the container may be located at a height

above the retort corresponding to the working pressure in the same. In this case also a water seal should be provided in the conduit between the retort and the container so as to prevent loss of heat by a flow of hot water up into the container as well as to prevent steam from entering the same.

The steam supply to the retort is suitably controlled by a temperature regulator whilst the building up of excessive pressure in the retort is prevented by means of a weight- or spring-loaded overflow- or relief-valve.

When the sterilizing stage is finished the steam supply is cut off and cooling water supplied to the retort, whereby the sterilizing liquid is displaced or forced out of the retort, preferably through the said relief valve to a container in which the liquid is accumulated, and from which it is returned to the retort for the next sterilizing stage. When the cooling stage is finished the cooling water is drained off and the retort opened for removal of the sterilized goods and for new charging.

By using a separate container for the accumulation of the displaced sterilizing liquid it is possible in retorts of the horizontal type, to use a liquid for sterilizing, inasmuch as the once heated sterilizing liquid may be used over again repeatedly, whereby not only is a material saving of fuel effected, but the advantage is obtained that the retort can be fed with a liquid at a temperature approximating sterilizing temperature, especially as the container may be kept under a pressure above the atmospheric pressure and at a corresponding temperature higher than 100° C. Contingently, steam may be supplied to the container in order to keep the temperature at the desired height. The container preferably is located above the retort so that oil and fat carried into the retort with the tins float to the top of the container from where it can be easily removed.

Finally the use of a separate container has the advantage that the steam pressure in the container, as soon as the retort is refilled, will apply an initial pressure to the liquid in the above described container or dome communicating with the retort.

The drawing illustrates diagrammatically an example of an embodiment of the invention. 1 is the retort and 2 an air-dome communicating with the retort through the water seal 3. The dome preferably is provided with a gauge glass for the inspection of the water-level in the dome. The building up of excessive pres-

sure in the retort is prevented by means of the weight-loaded relief or overflow valve 4 as will be brought out hereinafter.

From the weight loaded relief or overflow valve 4 a pipe 14 leads to the preferably isolated hot-water container 16 supported above the retort on frames 15, a non-return valve 17 being inserted in the pipe. A second pipe 18, provided with a stop valve 19 leads from the valve 4 to the drain pipe 20.

The heating of the sterilizing liquid and the building up of pressure in the retort is effected by means of steam supplied through the pipe 6, and regulated according to the temperature in the retort by a regulating valve 7, controlled by the temperature regulator 8. The steam supply pipe-line further is fitted with a by-pass-pipe 9, and with the necessary valves 10, so that the steam if necessary may be bypassed around the regulating valve 7. A stop-valve 11 for the steam is fitted at the inlet to the retort.

Upon completion of the sterilizing stage or step the steam supply is shut off and cooling water introduced into the retort through the pipe 12, which is provided with a stop-valve 13. If a drop in pressure in the retort should take place upon closing off the steam supply and the admission of the cooling water, this drop in pressure will at once be compensated for by the compressed air in the dome 2 forcing a quantity of liquid out of the dome back to the retort.

During the continued supply of cooling-water to the retort the water will displace the warm sterilizing-liquid and force the same through the relief valve 4 and the pipe 14 to the hot-water container 16, the stop valve 19 at this time being closed. The hot-water container 16 is provided with a safety valve 21 to which is connected a pipe 22 leading to the discharge pipe 20 so that steam and water may escape upon an excessive rise in pressure in the hot-water container, especially in the event of the container being completely filled. After transfer of the sterilizing liquid from the retort to the container 16, the valve 19 is opened so as to enable the introduction of cooling water to the retort to be continued, the non-return valve 17 preventing back flow of liquid from the container 16.

When the cooling is completed, the cooling-liquid is drained off from the retort through the valve 23 to the drain pipe 20, whereupon the end cover of the retort is opened for removal of the sterilized goods and renewed charging. For the next sterilizing stage or operation the hot liquid in the hot water container 16 is returned to the retort through the valve 24 and pipe 25.

The invention hereinbefore described is particularly advantageous if cans of aluminum are used, as this material does not possess sufficient elasticity, if deformed, to recover its original shape when the internal pressure of the can is removed. Likewise the invention is of advantage with light glass—or earthen ware containers where there is danger of bursting if the outside pressure is removed before the container with its contents has been cooled down sufficiently to effect a substantial reduction of the internal pressure.

What I claim is:

1. Apparatus for the sterilizing and subsequent cooling of food in closed containers, comprising in combination a single retort containing a liquid, means for supplying steam to the liquid in said

retort to sterilize the food in the containers and to build up a pressure in said retort not less than the pressure in the sealed containers within said retort, means for thereafter supplying cooling water to said retort through the bottom thereof, a container in communication with said retort, a valve intermediate the retort and container, said valve opening when the cooling water is admitted to said retort to permit the displaced sterilizing fluid in said retort to be forced into said container, and a valve controlled conduit connecting said container and retort for subsequent return of the displaced sterilizing fluid to the retort.

2. Apparatus for the sterilizing and subsequent cooling of food in closed containers, comprising in combination a single retort containing a liquid, means for supplying sterilizing steam to the liquid in said retort to sterilize the food in the containers and to build up a pressure in the retort not less than the pressure in the sealed containers within said retort, means for thereafter supplying cooling water to said retort through the bottom thereof, a sealed container in communication with said retort, a loaded valve intermediate the retort and said sealed container, said valve opening when the cooling water is admitted to said retort to permit the sterilizing fluid in said retort to be displaced and forced into said container, and a conduit connecting said retort and container for subsequent return of the displaced sterilizing fluid to the retort and a valve in said conduit.

3. Apparatus for the sterilizing and subsequent cooling of food in closed containers, comprising in combination a single retort for the closed containers, said retort adapted to contain water, means for supplying steam to said retort to build up a pressure therein not less than the pressure in the closed containers in the retort, a container for receiving the sterilizing liquid from said retort, a connection between said retort and container, a relief valve in said connection for preventing the building up of excessive pressure in said retort, means for admitting cooling water to said retort to displace the sterilizing water therein and force the same past said valve into said container, and an air dome in open communication with the retort the air in which is compressed by the fluid in the retort for counteracting fluctuations of the pressure in the retort.

4. Apparatus for the sterilizing and subsequent cooling of food in closed containers, comprising in combination a single retort adapted to contain water, means for supplying steam to said retort to sterilize the food in the containers and to build up a pressure in said retort sufficient to prevent deformation of the closed containers in the same, means for thereafter supplying cooling water to said retort at the bottom thereof, a container in communication with said retort, a loaded valve intermediate the retort and the container, said valve limiting the pressure that may be built up in the retort during the sterilizing operation and also opening when the cooling water is admitted to the retort, to permit the sterilizing water to be forced into said container, and a valve controlled conduit connecting said container and retort for subsequent return of the displaced sterilizing water to the retort.
